E. L. LEINBACH.
DOOR CHECK AND CLOSER.
FILED MAR. 7, 1921.

Inventor:
Edward T. Leinbach.
By: *John J. Gochman Jr.* Atty.

UNITED STATES PATENT OFFICE.

EDWARD L. LEINBACH, OF CHICAGO, ILLINOIS.

DOOR CHECK AND CLOSER.

Application filed March 7, 1921. Serial No. 450,348.

To all whom it may concern:

Be it known that I, EDWARD L. LEINBACH, a citizen of the United States, residing at Chicago, in the county of Cook and State 5 of Illinois, have invented certain new and useful Improvements in Door Checks and Closers, of which the following is a specification.

This invention relates to improvements in 10 door check and closer for automatically retarding a sudden closing and slamming of the door but which will allow the door to gradually close when released and at the same time will not interfere with an easy 15 opening movement of the door.

A further and more specific object of the invention is to provide an improved device 20 of this character embodying two members one of which constitutes a friction surface 25 and the other of which is wrapped about the friction surface, the members being relatively operated to cause a frictional gripping operation between the members as the door is closing, the grip between the members being automatically released as the door is opened.

A further object is to provide improved 30 means whereby energy will be stored during the opening of the door, and which energy will be spent when the door is released to cause the door to swing to a closing position.

To the attainment of these ends and the 35 accomplishment of other new and useful objects as will appear, the invention consists in the features of novelty in substantially the construction, combination and arrangement of the several parts hereinafter more fully described and claimed, and shown in the 40 accompanying drawing illustrating this invention and in which

Figure 1 is a top plan view.

Figure 2 is a vertical sectional view taken on line 2—2, Figure 3.

45 Figure 3 is a vertical sectional view taken on line 3—3, Figure 2.

Referring more particularly to the drawing the numeral 10 designates a hollow drum like structure which may be of any desired 50 size and configuration and constructed of any suitable material. This drum is preferably provided with a base 11, by means of which it may be anchored to a fixed support or to a swinging closure.

55 Supported within the drum 10, is a hub

12, which is secured to the drum in any suitable manner so as to be held against rotation and journaled in the hub 12 is an axle 13. This axle is preferably provided with a flange or shoulder 14, adjacent one end and 60 the other extremity of the axle is preferably threaded as at 15, to receive a nut or collar 16, the flange 14 abutting one end of the axle 13, and the collar 16 co-operating with the flange 14 for holding the drum 10 65 against displacement with respect to the axle.

Arranged within the drum 10 is a rotatable drum like element 17, which may also be of any desired size and constructed of any 70 suitable material. This drum like element 17 is preferably considerably smaller in external diameter than the internal diameter of the drum 10, so as to provide a space therebetween.

The drum 17 is connected with the axle 13, to rotate therewith in any desired or suitable manner preferably by means of the end 18, of the axle passing through a suitable opening in the drum 17, and also through an 80 element 19, which constitutes a closure for the drum 10, and which is rotatable with the drum 17, and the axle 13.

Arranged within the drum 17, is a coil 85 spring 20, which is coiled about the hub 12, and is anchored thereto by one extremity by means of a suitable anchoring device 21. The other end 22, of the spring 20, is anchored to the drum 17, in any suitable manner preferably by means of a lip 23, struck 90 up from the drum 17, and which lip passes through a suitable opening adjacent the end of the spring 22. The spring 20 is coiled about the hub 12; in such a direction that when the drum 17 is rotated in the direction 95 indicated by the arrow in Figure 2, the spring will be wound up so as to store energy therein but, when the drum 17, is released, in a manner to be hereinafter set forth, the energy thus stored in the spring 100 20, will operate upon the drum 17, to reverse its direction of rotation.

The drum 17, is preferably rotated by means of an arm 24, which is provided with an opening adjacent one end to receive the 105 end 18, of the axle 13, and a fastening device 25, is provided for securing the extremity of the arm 24 to the element 19, and the drum 17, so that when the arm 24 is moved in the direction indicated by the arrow in 110

Figure 1, it will rotate the element 19 and the drum 17 to wind up the spring 20.

This arm 24, may be of any desired size and configuration and pivotally connected to the 5 free end thereof as at 25, is a link 26, the free end 27 of which is preferably pivotally connected to a bracket 28, which latter may be secured to either the door 29, or the swinging closure 30.

10 Interposed between the drum like elements 10 and 17 is a band of flexible material 31, which may be of any desired width and constructed of any suitable material. This band 31, is coiled one or more times 15 about the drum 17, and the end 32, of the band is anchored by means of a fastening device 33, to the drum 10. This anchoring means may be of any desired construction but preferably embodies a plate having an 20 opening 34, adapted to receive a projection 35, on the end of the band 31.

Connected with the casing 10, is a screw 36, preferably arranged tangentially to the drum like element 17. This screw is supported for rotation by means of a suitable 25 casing or support 37, the head 38, of the screw being positioned so as to be readily accessible.

Threaded upon the screw 38, is a collar 39, preferably provided with an eye 40, into 30 which eye one end of a coil spring 41 is seated. The other end of the coil spring 41, is connected in any suitable manner with the free extremity 42 of the band 31, and the 35 spring 41, normally exerts its stress upon the band 31, in such a manner as to tend to wind or contract the band 31, about the drum 17. By adjusting the screw 38, the tension or stress of the spring 41, upon the band 31, 40 may be varied at will.

In use the casing or drum like element 10, may be secured either to the door 29, or closure 30, so that the free end of the link 26, 45 may be pivotally connected to the one to which the casing 10, is not secured.

The normal tendency of the spring 20, is to cause the closure 29, to close.

When the closure 29 is opened, the link 26 will cause the arm 24, to be moved in the 50 direction indicated by the arrow in Figure 1 and this will rotate the drum 17, in a direction to wind up the spring 20, to store energy therein. As the drum 17 is rotated in the direction indicated by the arrow in 55 Figure 2, the spring 41, will yield to permit the band 31 to expand. When, however, the closure 29, is moved in the opposite direction, the friction between the drum 17 and the band 31, will cause the band 31 to contract and frictionally grip the surface of the 60 drum 17, the spring 41, acting to hold the band 31 taut. This frictional gripping between the band 31, and the periphery of the drum like element 17, will retard the closing 65 movement of the door or closure 29,

while the energy of the spring 20, is being expended to move the closure in a closed position.

Obviously when the closure is again opened the spring 41, will yield to permit 70 the band 31 to expand so as not to interfere with the further opening movement of the closure.

Obviously many changes may be made in the details of construction and in the combination and arrangement of the several parts, within the scope of the claims, without departing from the spirit of this invention. 75

What is claimed as new is:—

1. A door check and closer embodying frictionally engaged members, one of the members being wrapped about the other member, means for rotating one of the members forwardly and backwardly with respect to the other member, the wrapped member being tightened upon the other member solely by the friction between the members when one of the members is moved in one direction with respect to the other member, and pivotally connected elements, the free end of one element being connected with the said rotatable member for operating the latter, the free end of the other element and the other of the said members being connected one with a swinging closure and the other with a fixed support. 80

2. A door check and closer embodying frictionally engaged members, one member being wrapped about the other member, one 85

of the members being adapted for a forward and backward movement with respect to the other of the members, the wrapped member being tightened upon the other member

solely by the friction between the members 90

when one of the members is driven in one direction with respect to the other member, the said friction operating to loosen the wrapped member when the direction of

movement of the driven member is reversed, 95

an arm connected with the driven member for moving it in one direction, a link connected with the arm, and means for returning the driven member in a reverse direction, the said link and the said other member

being connected one with a swinging closure and the other with a fixed support. 100

3. A door check and closer embodying frictionally engaged members, one of the members being wrapped about the other member, means for rotating one of the members forwardly and backwardly with respect to the other member, the wrapped member being tightened upon the other member solely by the friction between the members 105

when one of the members is moved in one direction with respect to the other member, the said friction operating to loosen the wrapped member when the direction of

movement of the driven member is reversed, an arm connected with the driven member for moving it in one direction, a link connected with the arm, and means for returning the driven member in a reverse direction, the said link and the said other member

being connected one with a swinging closure and the other with a fixed support. 110

4. A door check and closer embodying frictionally engaged members, one of the members being wrapped about the other member, means for rotating one of the members forwardly and backwardly with respect to the other member, the wrapped member being tightened upon the other member solely by the friction between the members 115

when one of the members is moved in one direction with respect to the other member, pivotally connected elements, the free end of one element being connected with the said rotatable member for operat-

120

ing the latter, the free end of the other element and the other of the said members being connected one with a swinging closure and the other with a fixed support. 125

5. A door check and closer embodying frictionally engaged members, one of the members being wrapped about the other member, means for rotating one of the members forwardly and backwardly with respect to the other member, the wrapped member being tightened upon the other member solely by the friction between the members 130

ing the latter, the free end of the other element and the other of the said members being connected one with a swinging closure and the other with a fixed support, and 5 means for varying the degree of friction between the said members.

4. A door check and closer embodying frictionally engaged members, one of the members being wrapped about the other 10 member, means for rotating one of the members forwardly and backwardly with respect to the other member, the friction between said members acting to tighten the wrapped member upon the other member when one of 15 the members is moved in one direction with respect to the other member, pivotally connected elements, the free end of one element being connected with the movable one of the members for operating it, the free end 20 of the other element and the other of the said members being connected one with a swinging closure and the other with a fixed support, one end of said wrapped member being anchored, and an anchored yielding element, 25 said element exerting its stress upon the wrapped member adjacent one end of the latter.

5. A door check and closer embodying two co-operating members, one of said members 30 being wrapped about the other member, an arm for imparting a pivotal movement to one of the members in one direction with respect to the other member, a link pivotally connected with the free end of the arm, and 35 means for reversing the direction of pivotal movement of the movable member, the said wrapped member co-operating with the other member in such a manner that its friction with the other member will cause it to contract when the pivotal member is actuated by 40 the first recited means and to expand when actuated by the second recited means.

6. A door check and closer embodying a pair of members movable relatively one with 45 relation to the other, one of said members being provided with a friction surface, a flexible friction band encompassing and co-operating with the said surface, the ends of the said band being connected with one of 50 the members, provisions whereby the movement of one of the members in one direction with respect to the other member will cause the said band to grip the said surface and when the movable member is moved in 55 the opposite direction, the grip or friction of the band upon the said surface will be relieved, and an arm connected with the movable one of the said members, the said arm and the other one of the said members being 60 connected one with a fixed support and the other with a swinging closure.

7. A door check and closer embodying a pair of members movable relatively one with 65 relation to the other, one of said members being provided with a friction surface, a flexi-

ble friction band encompassing and co-operating with the said surface, the ends of the said band being connected with one of the members, provisions whereby the movement of one of the members in one direction with 70 respect to the other member will cause the said band to grip the said surface and when the movable member is moved in the opposite direction, the grip or friction of the band upon the said surface will be relieved, an 75 arm connected with the movable one of the said members, and a link pivoted to the free end of the arm, the free end of said link and the other one of the said members being connected one with a fixed support and the 80 other with a swinging closure.

8. A door check and closer embodying a pair of members movable relatively one with relation to the other, one of said members being provided with a friction surface, a flexible friction band encompassing and co-operating with the said surface, the ends of the said band being connected with one of the members, provisions whereby the movement of one of the members in one direction with 85 respect to the other member will cause the said band to grip the said surface and when the movable member is moved in the opposite direction, the grip or friction of the band upon the said surface will be relieved, 90 an arm connected with the movable one of the said members for moving it in one direction, the said arm and the other of the said members being connected one with a fixed support and the other with a swinging 95 closure, and means for moving the said movable member in the reverse direction, the last recited means also operating to move the said closure.

9. A door check and closer embodying a pair of members movable relatively one with relation to the other, one of said members being provided with a friction surface, a flexible friction band encompassing and co-operating with the said surface, the ends of the 100 said band being connected with one of the members, provisions whereby the movement of one of the members in one direction with respect to the other member will cause the said band to grip the said surface and when the movable member is moved in the opposite direction, the grip or friction of the band upon the said surface will be relieved, 105 and an arm connected with the movable one of the said members, the said arm and the other one of the said members being connected one with a fixed support and the other with a swinging closure, the said provisions embodying a yielding element operating 110 upon the said band adjacent one end thereof.

10. A door check and closer embodying a rotary drum like element, a relatively stationary drum like element, means for rotating the drum in one direction, means for reversing the direction of rotation of the 115 120 125 130

- 4
- 5 rotary drum, and a friction band wrapped about the rotary drum and attached to the stationary drum in such a manner that its friction with the rotary drum will cause it to contract when the drum is rotated by the first recited means and to expand when the drum is rotated by the second recited means.
- 10 11. A door check and closer embodying a rotary drum like element, a relatively stationary drum like element, means for rotating the drum in one direction, means for reversing the direction of rotation of the rotary drum, a friction band wrapped about the rotary drum and attached to the stationary drum in such a manner that its friction with the rotary drum will cause it to contract when the drum is rotated by the first recited means and to expand when the drum is rotated by the second recited means, and adjustable means operable at will for contracting and expanding said band.
- 15 12. A door check and closer embodying a rotary drum like element, a relatively stationary drum like element, means for rotating the drum in one direction, means for reversing the direction of rotation of the rotary drum, a friction band wrapped about the rotary drum and attached to the stationary drum in such a manner that its friction with the rotary drum will cause it to contract when the drum is rotated by the first recited means and to expand when the drum is rotated by the second recited means, an adjusting screw mounted upon the stationary drum, a nut engaged by said screw, and an elastic element having one end connected with said nut, the other end of said elastic element being connected with one end of the said friction band.
- 20 13. A door check and closer embodying a pivotally mounted element, a relatively stationary drum like element, means for moving the pivoted element in one direction, means for reversing the direction of movement of the pivoted element, and a friction band wrapped about the rotary drum and attached to the said pivoted element in such a manner that its friction with the rotary drum will cause it to contract when the drum is rotated by the first recited means and to expand when the drum is rotated by the second recited means, and the stationary drum to tighten said band upon the rotary drum.
- 25 14. A door check and closer embodying a rotatable drum like element, a relatively stationary drum like element, means for rotating the drum in one direction, a coil spring between and connected to the two drums for reversing the direction of rotation of the drum, and a friction band wrapped about the rotary drum and attached to the stationary drum and in such a manner that its friction with the rotary drum will cause it to contract to grip the rotary drum when the drum is rotated in one direction and to expand when the drum is rotated in the opposite direction.
- 30 15. A door check and closer embodying a rotatable drum like element, a relatively stationary drum like element encompassing the rotatable drum, means for rotating the drum in one direction, elastic means between and connected with the two drums for reversing the direction of rotation of the drum, and a friction band wrapped about the rotary drum and attached to the stationary drum in such a manner that its friction with the rotary drum will cause it to contract to grip the rotary drum when the drum is rotated in one direction and to expand when the drum is rotated in the opposite direction.
- 35 16. In testimony whereof I have signed my name to this specification on this 4th day of March, A. D. 1921.
- 40 EDWARD L. LEINBACH.
